WIND INSTRUMENT AND KEY MOUNTING
FOR THE SAME

Earl O. Sylvester, San Leandro, Calif.

Application April 11, 1949, Serial No. 86,744

7 Claims. (Cl. 84—385)

1

This invention relates to wind instruments and particularly to finger key mountings for the same. The scattered overlapping and complicated mountings for finger keys on wind instruments, and particularly on saxophones and the like, detracts from the tone quality of the instrument, renders repairs very expensive, and adjustments almost impossible, necessitating the taking apart of the entire instrument. Previous instruments required a tedious breaking-in practice and period and were not quickly adaptable to the touch of the player.

The above and other disadvantages are obviated by my invention the features of which include the arranging of the finger keys into several groups, and mounting each group detachably independently of the other groups of finger keys; the providing of easy adjustment of the resiliency of the movement of each key to any touch; the adjustable stopping of any released key in a predetermined spaced position with respect to its tone hole; sectional removable key and control arrangement with separable connections where key actions must overlap from one group to a key of another group; eliminating needle springs, stiff key pivots, and a great number of complicated mechanisms and parts used in the past, thereby achieving simplicity and a more brilliant sound and tonal quality.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 is a perspective side view of a saxophone having my key mountings thereon.

Fig. 2 is a perspective side view of the saxophone from the side opposite from said first side.

Fig. 3 is a side view of a key mounting assembly.

Fig. 4 is a front view of a group of finger keys on a mounting bracket.

Fig. 5 is a sectional side view of another form of key mounting assembly.

2

Fig. 6 is a fragmental plan view of said other form of mounting.

Fig. 7 is a sectional detail view showing the adjustable spring tension and stop abutment for a key.

Fig. 8 is a partly sectional detail view showing the detachable fixing of the bracket on post or pin.

Fig. 9 is a plan view of another group of keys on my mounting device.

Fig. 10 is a side view of the group shown in Fig. 9.

Fig. 11 is a bottom plan view of the same, and

Fig. 12 is a view of inside face of the bell of the saxophone and the keys mounted thereon.

Fig. 13 is a fragmental sectional detail view of the octave hole control, and

Fig. 14 is a fragmental sectional view of the abutment and spring connection, taken on lines 14—14 of Fig. 13.

In the illustrative embodiments herein, I show the application of my invention to a saxophone, which has a conical body or tube 1 which is usually bent and flared to form a bell 2. In the oppositely bent mouth end 3 is the usual mouthpiece 4. The saxophone has thereon a plurality of tone holes 6 and corresponding keys 7 the disks 8 of which latter cover or uncover the respective tone holes 6 as desired. A stem 9 connects each disk 8 to a journal member such as a hub 10.

A plurality of adjacent keys 7 are grouped together and have their hubs 10 journaled on a pivot shaft 11 in bracket ears 12, which latter have holes 13 therethrough to accommodate said pivot shaft 11. The key stems 9 are extended in different directions to hold the disks 8 in registry with the respective tone holes 6. The bracket ears 12 extend from a bracket base 14 which in turn is detachably secured to the side of the saxophone. In the event of need for repair or adjustment or replacements the bracket base 14 is simply detached from the saxophone and the entire group of keys can be removed without disturbing any other group of keys or parts of the saxophone.

The bracket base 14 is a flat strip and fits longitudinally on the saxophone. The detachable securing is accomplished by providing on the saxophone a pair of bracket pins 16 which fit into spaced holes 17 through the sides of the bracket base so that the bottom 18 is in plane at right angles to the saxophone side, and parallel with the pins 16. A set screw 19 extends through the bottom 18 of the base and into each hole 17 for clamping the pin 16 in place and thus securing the entire assembly to the saxophone. For de-

taching the assembly of a group of keys and the bracket, the set screws 19 are loosened and the bracket is pulled off the pins 16, lifting the group of keys with it.

Inasmuch as certain saxophone keys overlap for simultaneous operation from one group to the other I provide a separable joint in overlapping extension key stems 21 as shown in Fig. 4. A socket 22 in the end of the extension stem 21 of one group of keys receives a reduced plug end 23 of the extension key stem 22 of other groups of keys. The second extension key stem 22 is preferably longitudinally adjustable and thus can be drawn out of the joint.

Each key is urged by adjustable resilient pressure to a predetermined released position. This is accomplished by a coil spring 24 which bears against the key to urge it to released position, which spring 24 is backed by an adjustable spring set screw 26, whereby the tension of the spring can be adjusted to the touch of the player. The clearance of the key from the tone hole is determined by a stop abutment 27 against which the key abuts in the released open position. This stop abutment is also a set screw adjustable for any selected spacing.

In the forms shown in Figs. 3, 4, and 7 to 11, each key hub 10 has a socket 28 therein offset to one side of the key pivot, in which socket 28 is held an end of the coil spring 24. The bracket base 14 has a threaded hole 29 therethrough, and the spring set screw 26 is adjusted in this hole to back the other end of the coil spring 24. Another threaded hole 31 through the bracket base 14 spaced on the other side of the key pivot holds the set screw abutment 27 in engagement with the key hub 10 when released and urged by the spring 24. This is repeated similarly for each key in the group.

For a single key the spring and abutment arrangement is as shown in connection with the octave key manipulator, wherein a yoke 32 is fixed on the key bar 33. A post 34 extends from the saxophone between the arms of the yoke 32. One of the yoke arms has therein the spring backing set screw 26 to back the coil spring 24 against one side of said post 34. The other yoke arm has therein the set screw abutment 27 abutting against the other side of said post 34 when the coil spring 24 turns the key bar 33.

The octave key manipulation is thus also regulated with adjustable resiliency and spacing. The octave key bar 33 is journaled in bearing brackets 36, which are of the split bearing type to allow easy detaching of the unit. One end of the bar 33 has a tubular stem 37 around it, which latter extends through the adjacent bracket 36. A side arm 38 on this tubular stem 37 holds a small key disk 39 over an octave tone hole 41, which disk 39 is normally held depressed by a key arm 42 of a remote key finger mechanism 43. On the end of the tubular stem 37 is a crank 44. The end of the key bar 33 has a bearing yoke 46 fixed thereon, in which latter is a bearing pin 47. A cam 48 is pivoted on the bearing pin and is also transversely slidable on a pin 49 on the crank 44. The cam 48 extends into a ring 51 around the neck 52 of the saxophone, which ring 51 is secured on the end of a curved lever 53. This lever 53 extends along the top of the saxophone to an upper octave tone hole 54 and carries a key disk 56 for said upper tone hole 54. The lever 53 is furcrumed on a pivot 57 between its ends, and is urged to key closing position by a leaf spring 58 thereunder. A finger extension 59 on the key bar

33 is depressed for turning the bar 33. The key arm 42 holds the key disk 39 onto the lower octave tone hole 41, hence the bearing yoke 46 turns the cam 48 and pulls it outwardly away from the saxophone thus pulling the ring 51 and moving the lever 53 to lift the upper tone hole cover disk 56. While the finger extension 59 is held depressed, and the remote key finger mechanism 43 is actuated to lift the key arm 42, the lower tone hole key disk 39 is released and the pressure of the leaf spring 58 will through the ring 51 pull the cam 48 against the crank 44 and turn the tubular stem 37 for lifting the side arm 38 and the lower octave hole disk 39, at the same time closing the upper octave hole disk 56. When the remote key finger mechanism 43 is released it will cause the pressing down of the lower octave hole disk 39 to closed position and thus shift the cam 48 back to its ring pulling position to again open the upper octave tone hole 54 as heretofore described.

In the modified form shown in Figs. 5 and 6 the bracket 61 is substantially the same as the bracket heretofore described, but a pair of pivot bars 62 are journaled therein and the key hubs and stems 63 are suitably mounted on said pivot bars 62. On a saxophone this mounting is used particularly on keys with long stems at comparatively long distance from their tone holes. In other respects the operation is substantially the same as the first form hereinabove described.

I claim:

1. A mounting device for a group of finger keys on a wind instrument, comprising spaced pins extended outwardly from the instrument, a bracket having a base and opposite ears extended from the base and having holes therein in registry with said pins and slidably fitting onto said pins, set screws at right angles to said holes to hold said bracket on said pins, and a group of finger keys pivotally supported between said ears and above said base in operative relation to the respective tone holes of the instrument.

2. A mounting device for a group of finger keys on a wind instrument, comprising spaced pins extended outwardly from the instrument, a bracket having a base and opposite ears extended from the base and having holes therein in registry with said pins and slidably fitting onto said pins, set screws at right angles to said holes to hold said bracket on said pins, and a group of finger keys pivotally supported between said ears and above said base in operative relation to the respective tone holes of the instrument, said base having a plurality of sockets in its top in registry with the finger keys, a coil spring in each socket bearing against the opposite key to urge the key into a predetermined released position, and an adjusting element in the bottom of each socket for adjusting the tension of said spring.

3. A mounting device for a group of finger keys on a wind instrument, comprising support elements extended from the side of the instrument, a bracket insertable over said elements, a base on said bracket, opposite ears extending from said base, releasable clamping means to fix said bracket onto said elements, a pivot bar extending above the base and being mounted in said ears, and a group of finger keys pivoted on said bar and extended into operative position with respect to the respective tone holes of the instrument.

4. A mounting device for a group of finger keys on a wind instrument, comprising support elements extended from the side of the instru-

ment, a bracket insertable over said elements, a base on said bracket, opposite ears extending from said base, releasable clamping means to fix said bracket onto said elements, a pivot bar extending above the base and being mounted in said ears, and a group of finger keys pivoted on said bar and extended into operative position with respect to the respective tone holes of the instrument, and adjustable coil springs on said base bearing against the respective finger keys to urge said keys to the respective released position.

5. A mounting device for a group of finger keys on a wind instrument, comprising support elements extended from the side of the instrument, a bracket insertable over said elements, a base on said bracket, opposite ears extending from said base, releasable clamping means to fix said bracket onto said elements, a pivot bar extending above the base and being mounted in said ears, and a group of finger keys pivoted on said bar and extended into operative position with respect to the respective tone holes of the instrument, and adjustable coil springs on said base bearing against the respective finger keys to urge said keys to the respective released position, and adjustable stop abutments on said base opposite the respective keys to stop said keys in a predetermined position when said keys are urged by said springs to the released position.

6. In a wind instrument having tone holes thereon, a plurality of finger keys for the respective tone holes, said fingers being arranged in a plurality of groups, a separate detachable mounting device of each group of finger keys, said mounting device including a bracket, detachable means to secure said bracket on the instrument,

and means on the bracket for pivotally supporting the keys on the bracket in operative relation to said tone holes, and overlapping separable connections between certain of the keys of adjacent groups.

7. In a wind instrument having tone holes thereon, a plurality of finger keys for the respective tone holes, said fingers being arranged in a plurality of groups, a separate detachable mounting device of each group of finger keys, said mounting device including a bracket, detachable means to secure said bracket on the instrument, and means on the bracket for pivotally supporting the keys on the bracket in operative relation to said tone holes, adjustable resilient device on each bracket to urge the keys to released position, and adjustable stops on the brackets to abut said keys in predetermined released relation to the tone holes.

20 EARL O. SYLVESTER.
